United States Patent Office.

WILLIAM H. JACKSON, OF NEW YORK, N. Y.

Letters Patent No. 92,974, dated July 27, 1869.

ORNAMENTAL BACK FOR FIRE-PLACES.

The Schedule referred to in these Letters Patent and making part of the same.

To all whom it may concern:

Be it known that I, WILLIAM H. JACKSON, of the city of New York, in the county and State of New York, have invented a new and improved Ornamental Back for Open Fire-Places; and I do hereby declare that the following is a full, clear, and exact description thereof, which will enable others skilled in the art to make and use the same, reference being had to the accompanying drawing forming part of this specification.

The object of this invention is to construct an ornamental back and sides for open fire-places, which may be inserted in the said fire-place, and forming the back of a grate, as may be required, and thus relieve the eye from looking on a blackened soapstone as now used in a handsomely-finished fire-place, the construction of which will be fully understood from the following description.

Figure 1 represents a front view of my improved back for fire-places.

Figure 2 is a sectional plan view of the same, showing it attached to one of the sides.

Similar letters of reference indicate corresponding parts.

In this case the letter A represents a frame of cast-iron or other metal, the said frame being cast with a diamond or other pattern in which colored tiles or designs, B, may be set.

The letters C represent hooks cast on the flange of the sides of the back, for the purpose of locking into corresponding hooks on the sides D, as shown in fig. 2.

The face of the castings is enamelled, thus giving the back and sides of an open fire-place a handsome finish, which will be in keeping with, and add to the beauty of a first-class fire-place.

Having thus described my invention,

What I claim as new, and desire to secure by Letters Patent, is—

An ornamental back and sides for open fire-places, consisting of a cast-metal frame, enamelled on its face with diamond or other shaped spaces filled with tile of various colors, the said back and sides locking together in the manner and for the purpose substantially as herein set forth, shown, and described.

WILLIAM H. JACKSON.
